(57) **CLAIM**

The ornamental design for a screw drill holder, as shown and described.

DESCRIPTION

FIG. 1 is a perspective view illustrating an embodiment of a screw drill holder;

FIG. 2 is a left side elevation view of the screw drill holder;

FIG. 3 is a right side elevation view of the screw drill holder;

FIG. 4 is a front elevation view of the screw drill holder;

FIG. 5 is a rear elevation view of the screw drill holder;

FIG. 6 is a top plan view of the screw drill holder; and,

FIG. 7 is a bottom plan view of the screw drill holder.

The broken lines in the drawings depict environment that forms no part of the claimed design.

1 Claim, 4 Drawing Sheets
